SELECTOR SWITCH SUITABLE FOR USE IN TELEPHONE SYSTEMS

Application filed May 31, 1930, Serial No. 458,044, and in Great Britain June 26, 1929.

This invention relates to selector switches suitable for use in telephone systems, which comprise groups or levels of stationary contacts and associated sets of movable contacts or brushes, one for each group or level, and means for selecting a particular set of the movable contacts or brushes for engagement with a particular group or level of stationary contacts.

10 Hitherto in selecting switches of this type separate driving means have been used for the movement of the said movable contacts or brushes and for operating the means for selecting a particular set of said movable contacts or brushes.

15 The present invention has for its object an improved selecting device in which the said movable contacts and the means for selecting a particular set of brushes are operated by means of one common driven gear and one common drive.

According to a feature of this invention in its application to a rotary selector switch of the kind in which a particular set of brushes 20 on a rotatable brush carriage is selected for engagement with a set of stationary contacts by means of a trip spindle or cam shaft, the trip spindle or cam shaft is brought into its operative position simultaneously with a preliminary movement of the brush carriage.

According to another feature of the invention the trip spindle or cam shaft is driven from a continuously rotating power driven shaft through the brush carriage arranged 25 therebetween.

30 A further feature of the invention relates to an intermediate wheel mounted on the shaft of the brush carriage and adapted to be brought into engagement with a continuously rotating wheel fixed on a power driven shaft and moreover with a wheel mounted on the trip spindle or cam shaft. The said intermediate wheel may be a flexible gear wheel which is normally warped out of engagement 35 with the said continuously rotating wheel and/or the wheel of the trip spindle by armatures of clutch magnets associated with the brush carriage and the trip spindle which operate upon the said flexible wheel.

40 According to further features of the in-

vention the home position and the ratio of the speed of the trip spindle and the brush carriage are such that the trip spindle can reach any of its tripping positions before the brush carriage passes in front of the trip 35 spindle cam adjusted to the tripping position, and that the trip spindle reaches its home position before the brush carriage has reached its own home position when the switch is restored to normal.

45 Further features of the invention relate to an improved and simplified construction of the clutch controlling the engagement of the said flexible wheel with the trip spindle wheel and the power driven wheel, and to a 65 plunger mechanism operated by the brush carriage when it reaches its home position in order to open the homing circuit of the switch.

50 The above and other features of the invention will be more readily understood from the following description and the drawings of one embodiment thereof, but it will be understood that the invention is in no way limited to this particular embodiment.

55 Referring now to the drawings, Fig. 1 is a front elevation of the selector with a portion of the power driven main shaft shown in dotted lines. Fig. 2 is a plan of the selector switch shown in Fig. 1. Fig. 3 shows schematically the common driven gear and the common drive according to this invention as applied to the selector shown in Figs. 1 and 2 and Fig. 4 shows a modification of this driving system.

60 To the selector frame (1) is attached the terminal arc by means of top and bottom plates (2). The terminals (28) are arranged in blocks (3) of which only a few numbers are shown in the drawings. The selector frame carries also the clutch magnets (4, 5) which serve to control the driving gear formed by the wheels 35, 36 and 37. The manner of operation of this gear will be described hereinafter. Furthermore the frame 65 (1) carries a set of commutator brushes (7) which cooperate with a commutator (17) located at the upper end of the trip spindle (11), and a plunger mechanism (20) arranged to operate a set of home contacts (19) 70

when the brush carriage reaches its home position. This roller is pivoted in a lower bearing (15) which is also adjustable and in an upper bearing (16). These bearings as well as the bearings carrying the brush carriage and the trip spindle are arranged in horizontal extensions of the selector frame. 70

5 The brush carriage (8) is pivoted in the centre of the frame in an upper and lower bearing (9, 10). The lower bearing (9) is adjustable so as to permit the exact alignment of the brushes (25) of the brush carriage with the horizontal terminal rows of the arc. On each side of the frame portion carrying the upper bearing (10), a set of brushes (6) is mounted in a suitable manner. The brushes (6) engage the commutator rings (18) located at the upper end of the brush carriage, whereby electrical connection is established between the brushes (25) of the brush carriage and the associated selector circuit. The brushes (25) are threaded 75 on a spindle which is rigidly secured to the lower and upper plate of the brush carriage by means of screws as shown in Fig. 2 and they are normally held in the unoperated position by latch blocks (24) of insulating 80 material which are pivotally mounted on another spindle of the brush carriage. 85

10 Fig. 2 of the drawings shows the brushes (25) and the latch blocks (24) in their unoperated position and Fig. 1 shows the rear view of the brush carriage. As it may be 90 seen from Fig. 2 the latch blocks (24) are pressed against the brushes (25) by comb springs (26) mounted on the rear portion of the brush carriage. These comb springs are 95 however not shown in Fig. 1. The brushes (25) are kept retracted and out of the range of the arc terminals (28) by these latch blocks against pressure exerted upon them by comb 100 springs (27) which are also mounted on the rear portion of the brush carriage but insulated therefrom, and which tend to force the brushes outward. The comb springs (27) serve also to make the electrical connection 105 between the commutator rings (18) and the brushes (25). 110

15 To the left of the brush carriage is pivoted in an adjustable lower bearing (12) and an upper bearing (13) the trip spindle (11), which carries a rigid gear wheel (37) secured to the lower end of the spindle and at 115 its top end the already mentioned commutator (17). The trip spindle or cam shaft carries furthermore a number of cams (11') which correspond to the different groups or 120 levels of the selector arc and which are spirally arranged around the shaft (11) in a well known manner. 125

20 To the right of the brush carriage is a roller (14) which resets the brushes (25) as 130 they pass on their way in completing a rota-

10 The driving gear of the brush carriage and the trip spindle will now be described. The driving system comprises as stated in the foregoing the three gear wheels 35, 36 and 37. The gear wheel 35 is the driving wheel and is rigidly fixed on the continuously rotating power driven bay shaft (38). The gear wheel (36) consist of a thin flexible disc mounted at the bottom end of the brush carriage 8 and rotatable therewith and the wheel (37) is secured to the lower end of the trip spindle. The flexible wheel (36) is normally warped out of engagement with the continuously rotating wheel (35) and with the trip spindle wheel (37) by means of the armatures (29, 41) of the clutch magnets (4) and (5) respectively. The said clutch magnets (4) and (5) are very similar one to another and therefore only one will be described in detail. The clutch magnet (4) is mounted on a rectangularly bent support which is fixed by screws to a vertical extension (39) of the selector frame. The armature (29) is pivoted at one end in extensions (32) provided on the said support and carries adjacent to its pivoted end a vertical extension (30). The outer end of this vertical extension is engaged by a helical spring (31) the other end of which is secured to an adjustable angle lever (48) pivotally mounted on the said support. This angle lever (48) may be shifted by means of a screw (53) screwed in the said support and operating on the free arm of the angle lever, whereby the tension of the spring may be adjusted to the desired degree. This spring holds the armature (29) in its unoperated position in which position the free end of the armature engages the wheel (36) and warps it out of engagement with the wheel (35). The free end of the armature (29) carries a piece (33) which engages the flexible gear wheel (36) and presses it against a back stop (34), whereby the brush carriage is immediately stopped in the desired position when the armature releases. 110

25 The clutch magnet (5) is mounted in the same manner, however its armature (41) carries at its outer end a roller (42) operating upon the flexible disc (36). This roller is provided to permit the further movement of the brush carriage when the flexible wheel is warped out of engagement with the trip spindle wheel (37). In order to secure the trip spindle in the selected tripping position a piece 52 is provided on the portion of the armature which passes over the trip spindle wheel. This piece acts as a brake when the trip spindle clutch (5) releases and there- 115

fore the trip spindle is held in the desired position.

As mentioned in the foregoing the selector frame carriers at the right upper portion 5 a plunger mechanism (20). The said mechanism comprises a pivotally arranged lever (21) which engages with its free end a horizontally arranged plunger (20). The opposite end of the plunger engages a con- 10 tact spring (19). Normally the said plunger is forced by the said contact spring in the path of a projection (23) provided on the upper plate of the brush carriage. When however the brush carriage reaches the home 15 position indicated in Fig. 2 by the line (50), the said projection engages the lever (21) and thereby forces the plunger (20) to operate the springs (19) which are mounted on a support (40) fixed to the selector frame.

20 The operation of the selector will be now described. Fig. 3 shows schematically the driving arrangement illustrated in Figs. 1 and 2 and reference may be made to that figure for a complete understanding.

25 When the selector is taken into use the clutch magnet (4) operates and brings the flexible gear wheel (36) into engagement with the continuously rotating drive (35) which is fixed to the power driven bay shaft 30 (38).

At the same time the clutch magnet (5) has been operated which removes the brake (52) from the trip spindle wheel (37) and allows the flexible wheel (36) to come into 35 engagement with the trip spindle wheel, so that the trip spindle (11) rotates together with the brush carriage (8). As soon as the trip spindle stands in the required position to unlatch the brushes of a given level, 40 the clutch magnet (5) releases. The roller (42) mounted on the armature (41) of the trip spindle clutch disengages the flexible gear wheel (36) from the trip spindle wheel (37) and the brake (52) mounted on same 45 armature is pressed on the wheel (37) and stops the trip spindle (11).

Clutch magnet (4) however remains operated so the brush carriage (8) continues its rotation and in passing the trip spindle (11) 50 one set of brushes (25) is released by the associate latch block (24) engaging one of the cams (11') projecting in its path. The brush carriage thereafter continues its rotation until it is stopped on an arc terminal, which represents either a free trunk the 55 case of a group selector or a selected line in the case of a final selector by deenergization of the clutch magnet (4).

At the end of a call the clutch magnets 60 (4) and (5) are again operated. The brush carriage (8) and the trip spindle (11) rotate until they both reach their home positions. As the trip spindle will reach its 65 home position first the magnet (5) will release first.

The home position (line 50) of the brush carriage and the ratios between the speed of the trip spindle and the brush carriage are determined in such a way that, when starting the selector, the trip spindle can reach any of the tripping positions, for example that for the 10th level, before the latch blocks of the brush carriage pass in front of the tripping position indicated by the dotted line which connects the centre of the brush carriage shaft with that of the trip spindle. 70 75

When returning home after completion of a connection with the last terminal of the arc, the trip spindle will reach the home position before the brush carriage has reached its own home position. It will be understood that in passing the resetting roller (14) the previously tripped set of brushes (25) is returned to normal, being relatched by the latch block (24). 80 85

The foregoing is also shown in Fig. 2 of the drawing in which the angle (A) indicates the angular distance within which the brush carriage and the trip spindle are restored to their normal positions, whereas the angle (B) shows the angular distance within which the trip spindle can be rotated from the home position to the last or 10th tripping position. 90 95

It is to be noted that during rotation of the brush carriage, the roller (42) mounted on the armature of the clutch magnet (5) rolls over the flexible gear wheel (36).

Fig. 4 illustrates the same principle, but in this case the flexible gear wheel (36) is pushed into engagement with the trip spindle wheel (37) by the roller (42) mounted on the armature (41) of clutch (5). 100

When the clutch magnet (5) releases, the flexible gear wheel (36) disengages from the trip spindle wheel (37) under the influence of its own tension. At the same time the brake (52) mounted on the lower side of the armature stops the trip spindle. 105 110

It will be observed that with the construction according to this invention the shaft (38) may be arranged in any convenient position in front of the switch so as to be easily reached for attendance purposes. 115

It will be further seen that all parts of the switch which have to be inspected from time to time are easily accessible since they are all arranged on the front side of the switch. 120

At the same time it must be pointed out that the selector according to this invention requires less mounting space than any former construction of this type of selector, and that due to the use of only one driving gear and one drive which is common to the brush carriage and the trip spindle the costs are also reduced. 125

It will be understood that while the foregoing description applies to a switch using a gear drive of a particular form shown, the 130

invention may be applied to any form of gear drive. Further it will be clear that the application of the invention is in no way limited to the particular type of switch 5 shown and that it may be applied to any form of selector in which gear drive is used and in which there are more than one movable part.

What is claimed is:

- 10 1. In a selector switch comprising a plurality of sets of brushes and mounted on a movable carriage, a device for selecting a particular set of said brushes, and means to operate said device by a movement of said carriage preliminary to the movement thereof which advances the brushes over the bank of the selector.
- 15 2. A selector switch comprising a plurality of contacts carried on a movable brush carriage said contacts being normally in an inoperative position with respect to the selector bank contacts and in which a particular set of said contacts is brought into operative position by a multi position trip spindle, characterized in this that means is provided whereby the said trip spindle is operatively connected to move with said brush carriage whereby it is brought into one of its operative positions simultaneously with a preliminary movement of the brush carriage.
- 20 3. In a selector switch having a brush carriage and a trip spindle for selecting a particular set of brushes out of a plurality of sets mounted on the brush carriage, the combination of a driving wheel for the brush carriage, a driving wheel for the trip spindle and means for operatively connecting said wheels for part of the brush carriage cycle.
- 25 4. A selector switch having a brush carriage and a trip spindle cooperating therewith, characterized in this that the brush carriage is provided with a gear wheel adapted to be driven from a continuously rotating power driven shaft, which gear wheel is also arranged to drive the trip spindle during 30 part of the brush carriage cycle.
- 30 5. A selector switch comprising a brush carriage, a flexible gear wheel on said brush carriage, a trip spindle having a gear wheel 35 mounted thereon, means for warping said flexible gear wheel into and out of engagement with a driving gear, and means for warping said flexible gear wheel into and out of engagement with said gear wheel mounted on the trip spindle during the brush carriage cycle.
- 40 6. A selector switch according to claim 5 wherein said means for warping said gear wheel are controlled by electromagnets which 45 are energized simultaneously.
- 45 7. A selector switch comprising a rotatable brush carriage, a rotatable trip spindle, a plurality of brushes carried by said brush carriage, a plurality of spirally arranged 50 cams on said trip spindle for tripping said

brushes, means for rotating said trip spindle during the rotation of the brush carriage to bring a particular cam into the path of the brush carriage, means for rotating said carriage past said trip spindle, said means comprising intergaging gear wheels on said brush carriage and trip spindle, the ratio of such gear wheels being such that said trip spindle is adapted to reach any one of its positions for tripping said brushes prior to the brush carriage passing the said trip spindle.

8. A selector switch comprising in combination a frame, a brush carriage journalled for rotation in said frame, a trip spindle journalled for rotation in said frame, means for rotating said brush carriage, means on said brush carriage for rotating said trip spindle during the rotation of the brush carriage, means for stopping rotation of said trip spindle and means independent of said last mentioned means for stopping rotation of said brush carriage.

9. A selector switch comprising in combination a frame, a brush carriage journalled for rotation in said frame, a trip spindle journalled for rotation in said frame, a gear wheel on said brush carriage, a gear wheel on said trip spindle, an electromagnet on said frame and means under control of said electromagnet for engaging and disengaging said gear wheels during the brush carriage cycle.

10. A selector switch as claimed in claim 9 wherein a second electromagnet is provided on said frame and means under control of said second electromagnet effects the engagement and disengagement of the gear wheel on the brush carriage with a source of driving power common to a plurality of selector switches.

11. A selector switch as claimed in claim 9 wherein the gear wheel on the brush carriage is in the form of a flexible disc and said means under control of the electromagnet carries a roller for engaging said disc to allow rotation of the latter when warped out of engagement with the gear wheel on the trip spindle.

12. A selector switch as claimed in claim 9 wherein said means under control of the electromagnet comprises a brake device cooperating with the trip spindle and adapted to arrest its rotational movement.

13. In a selector switch as claimed in claim 8 the combination of a plunger slidably mounted on said frame, a set of contacts on said frame adapted to be operated by said plunger and means on the brush carriage for operating said plunger.

In witness whereof, we hereunto subscribe our names.

GERALD DEAKIN.

LOUIS JEAN JOSEPH SCHREIBER. 130
